GAS PRESSURE OPERATED CORK REMOVER

Serge Mourreau, 7 Chemin des Palettes, Grand-Lancy,
Geneva, Switzerland, and Marcel Gonnet, 12 Blvd.
Georges Favon, Geneva, Switzerland

Filed Apr. 26, 1963, Ser. No. 74,624

Claims priority, application Switzerland Oct. 26, 1962

Term of patent 14 years

(Cl. D44—29)

FIG. 1

FIG. 2

FIG. 3

FIG. 4

FIG. 1 is an elevational view of a gas pressure operated cork remover showing our new design, in inoperative condition;

FIG. 2 is an elevational view thereof in operative condition with the needle protector attached at the opposite end;

FIG. 3 is a top plan view of the article as shown in FIG. 1; and

FIG. 4 is a bottom plan view of the article as shown in FIG. 2.

We claim:

The ornamental design for a gas pressure operated cork remover, as shown and described.
